UNITED STATES PATENT OFFICE.

FRANK HOHENSTEIN AND HENRI HOHENSTEIN, OF ROCHESTER, NEW YORK.

COAT COLLAR.

Application filed March 28, 1927. Serial No. 178,837.

The object of this invention is to provide a new way of forming collars for coats so that any stripes or other design in the front of the collar will match the stripes in the 5 lapel and front of the coat and the stripes in the back of the collar will match the stripes in the back of the coat.

This and other objects of this invention will be fully illustrated in the drawings, 10 described in the specification and pointed out in the claims at the end thereof.

In the accompanying drawing:

Figure 1 is a side elevation of a portion 15 of a coat provided with our new form of collar.

Figure 2 is a rear elevation of a portion 20 of a coat provided with the new form of collar.

Figure 3 is a detail plan view of the three 25 sections making up the lapel and one-half of the collar, two of the sections being partly broken away.

Figure 4 is a side elevation of a portion 30 of a coat provided with a slightly modified form of the new collar.

Figure 5 is a rear elevation of the coat 35 and collar illustrated in Figure 4.

Figure 6 is a detail plan view of the two 40 sections making up the lapel and one-half of the collar illustrated in Figures 4 and 5.

In the several figures of the drawings like 45 reference numerals indicate like parts.

The new method of making a coat collar 50 forming the subject matter of this invention provides a collar, which when sewed onto a coat will have its stripes or other design matching the front as well as the back of the coat, thus giving the coat a much better appearance than is possible with the present 55 day method of making a coat collar.

As illustrated in Figures 1 to 3 and Figures 4 to 6 the lapel may be made so as to either have the end section 2^A attached separately thereto as illustrated in Figures 1 and 45 3 or may be made with the end section of the collar 2 forming an integral part of the lapel as illustrated in Figures 4 and 6. The coat to which our new collar is attached is made in the usual manner. The fabric from 50 which the coat illustrated in the drawing is made is shown as having stripes, in order to more clearly bring out the object of this invention. While we have illustrated the fabric as having stripes it is, however, understood that the invention is applicable to 55 other designs such as checks etc. in which

the alignment of the designs in the particular manner made possible by this invention, adds to the appearance of the whole of the coat.

In the form illustrated in Figures 1 and 3 the lapel 1 and the end sections 2^A of the collar 2 are sewed together and extend to the shoulder line 4 of the coat. In cutting the coat front from figured goods, it is customary to cut the front section so that the lines or figures extend substantially parallel to the front edge 5 of the coat while the back of the coat is cut so that the stripes will extend vertically therein. The division line 76 between the front section of the coat and the back is at the shoulder line 4. In piecing the end sections 2^A to the collar, the goods of the end sections are arranged so that the stripes or figures thereof form a continuation 75 of the stripes and figures of the lapel 1. The end sections 2^A that is pieced to the top of the lapel thus forms a continuation thereof as far as the stripes or figures of the fabric are concerned, and this continuation 80 of the stripes extends to the central portion 2 of the collar which is attached to the end section 2^A with the seam between the end section and the center section 2 of the collar located in line with the shoulder line 4 formed 85 by the seam between the front and back of the coat. The lines in the back of the coat are thus continued by the lines in the center portion of the collar and give the 90 whole of the back of the coat the appearance illustrated in Figure 2 in which the lines of the collar match, perfectly with the lines in the back of the coat.

In the lapel 1 of the coat and the portion 95 2^A of the collar extending to the front of the coat and forming a continuation of the lapel, the lines or stripes of the material may be placed angularly to the lines of the front of the coat as illustrated in Figure 1, or the material may be arranged so that the 100 lines of the lapel will be parallel to the lines in the front of the coat as illustrated in Figure 4 of the drawing. In either case the appearance of the lapel is improved by the fact that the portion of the collar forming 105 the continuation of the lapel has its lines or figures extending in the same direction as the lines or figures of the lapel as far as it can be seen when viewing the coat from the front. This is as far as the shoulder seam 110 which is the meeting point between the front and back of the coat, and which in this in-

vention also forms the dividing line between the front sections 2^A and rear section 2 of the collar.

In the form of lapel illustrated in Figures 4 and 6 the same result is secured by making the lapel and the front section of the collar integral with each other that is, these two parts are cut out of the same piece of goods. This will do away with the division line 10 between the top of the lapel and the end section of the collar so that only one seam, the shoulder seam between the rear of the collar and the front section is needed between the lapel and the collar. The layout 15 of the lapel and collar with relation to each other and the front and back of the coat is illustrated in Figure 6.

The manner of making the collar and lapel illustrated in Figures 4 and 6, in which 20 the only seam between them is in line with the shoulder seam of the coat, makes it possible to make the stripes or figures of the material in the collar and back of the coat run parallel and in line with each other in 25 the same way as is described in connection with the collar and lapel construction illustrated in Figures 1 and 3 and the stripes or figures of the lapel and front portion of the collar may be made so as to be either 30 angular to or parallel with the front of the coat as illustrated in Figures 1 and 4.

Both methods of making the collar therefore secure the same result namely, they locate the dividing seam between the front 35 and back of the collar in line with the shoulder seam of the coat allowing the lapel and front of the collar to have their lines form continuations of each other and either be parallel to or be at an angle to the front 40 of the coat while the stripes or figures of

the rear portion of the collar will be parallel to and in line with the stripes or figures of the back of the coat.

We claim:

1. A collar and lapel for a coat made of 45 striped or figured material and having a shoulder seam, said collar comprising a central or rear section having its stripes or figures parallel and in line with the back of the coat, end or front sections attached to said 50 rear or central section and having with the seam between the end front section and the central or rear section located in line with and forming a continuation of the shoulder seam between the front and back of the coat, 55 a lapel forming a continuation of said end or front section of said collar and having its stripes or figures in line with the stripes or figures of said end or front section of said collar. 60

2. A collar and lapel for a coat made of striped or figured material having a shoulder seam between the front and back of the coat, said collar having its stripes or figures in line with and parallel with the back of the 65 coat and extending from one shoulder seam to the other shoulder seam, said lapel having its stripes or figures in a predetermined position with relation to the front of the coat and an extension at the top of the lapel 70 with its stripes or figures forming a continuation of the stripes or figures of the lapel, said extension extending to the shoulder seam of the coat and forming a continuation of the collar at the front of the coat. 75

In testimony whereof we affix our signatures.

FRANK HOHENSTEIN.
HENRI HOHENSTEIN.
